VALVE CONTROLLING MEANS FOR LIQUID
DISPENSING SYSTEMSWilliam L. Marden, Jackson Heights, N. Y., as-
signor to Neptune Meter Company, a corpora-
tion of New Jersey

Application December 1, 1933, Serial No. 700,482

11 Claims. (Cl. 137—68)

This invention relates to valve controlling means and particularly to means for controlling a valve associated with a pump for dispensing gasoline from a storage tank.

Where gasoline is dispensed from a storage tank by a suction pump it is desirable, in order to avoid unintentional defrauding of customers and improper operation of the registering mechanism associated with the pump, to prevent the discharge of air by the pump in case the level of gasoline in the tank falls below the intake end of the pipe through which gasoline is withdrawn. Inasmuch as gasoline frequently contains a certain amount of water, which being of higher specific gravity settles to the bottom of the storage tank and accumulates over a period of time, it is also desirable to prevent the discharge of water by the dispensing pump. Therefore, it is an object of the present invention to prevent discharge of air or water from a gasoline storage tank by a dispensing pump.

One feature of the present invention is the provision of a valve associated with the discharge pipe from a gasoline storage tank and its control to permit suction between the pump and tank when the gasoline line is above the inlet of the discharge pipe and to cut off suction and prevent discharge of air by the pump when the gasoline level falls below the inlet.

A second feature resides in the provision of means for controlling the above mentioned valve to cut off suction between the dispensing pump and storage tank for preventing the undesired discharge of water accumulated in the tank.

Another feature resides in means for controlling the valve to prevent discharge of water although the gasoline level may be above the inlet of the discharge pipe.

In the drawing:

Figure 1 is an elevational view, partly in section and partly broken away, showing a dispensing pump and storage tank embodying the present invention;

Figure 2 is an enlarged elevational view of a portion of Figure 1 showing the valve control means; and

Figure 3 is a bottom plan view of part of the control means shown in Figure 2.

In the drawing, the numeral 10 designates a conventional dispensing pump of the suction type for withdrawing gasoline from a storage tank 11 through a pipe 12. Pipe 12 extends into the tank and has its inlet end positioned above the bottom of the tank whereby pump 10 may withdraw liquid

stored in the tank so long as its level does not fall below the inlet end of the pipe.

A valve 13 is provided for controlling suction between the interior of tank 10 and pipe 12. In the form shown, valve 13 comprises a cap carried by a lever 14 pivotally mounted at 15 on a bracket or lug 16 adjacent the inlet end of pipe 12 and provided with a float member 17 adapted to float in gasoline. With this arrangement, when the gasoline level is above the inlet end of pipe 12 valve 13 is normally held open to permit the withdrawal of gasoline and when the liquid level falls below the inlet of the pipe 12 the float member 17 acts to close valve 13, thus preventing the discharge of air by pump 10 and the improper operation of the registering mechanism 18 thereof.

Levers 20 having portions straddling the end of pipe 11 are also pivoted at 15 and support a float 21 which sinks in gasoline and floats in water. Levers 20 extend beyond pivot 15 and carry a stud 22 engageable with lever 14 to operate the latter for closing valve 13. Float 20 acts to cause closing of valve 13 in the event that water accumulates in tank 11 and rises to such a level that there is danger of pump 10 discharging water instead of gasoline, the relations of the floats 17, 21 and their levers 14, 20 being such that the buoyancy of float 17 may be overcome although the gasoline level is above the inner end of pipe 11.

In the foregoing description I have described the invention with particular reference to its application in dispensing gasoline. It is to be understood that the invention has other applications and may be applied wherever it is desired to dispense a liquid by pump means or otherwise from a storage space wherein are present one or more other liquids that are non-miscible therewith and differ therefrom in their specific gravities.

From the foregoing description it will be seen that the valve and its controlling mechanism which I have provided are effective to insure that only gasoline will be discharged by the dispensing pump and that neither air nor water may be discharged to cause dissatisfaction on the part of customers or interference with the accuracy of customers or interference with the accuracy of 45 sales.

As there are many changes and variations which may be made in the form of the invention without departing from the spirit thereof, it is intended to include all such changes and variations within the scope of the invention.

I claim:

1. In a liquid-dispensing system including a gasoline storage tank, a suction pump, and a

5 pipe connected to said pump and extending into said tank with its inlet above the bottom of the latter for withdrawing liquid therefrom; a valve operable for controlling passage of liquid through said pipe; means responsive to the presence of gasoline in said tank for opening said valve to permit the withdrawal of gasoline when the level thereof is above said inlet; and means responsive to the presence of water in said tank operating 10 to close said valve when water accumulating in said tank rises to a determined level.

15 2. In a liquid-dispensing system including a gasoline storage tank, a suction pump, and a pipe connected to said pump and extending into said tank with its inlet above the bottom of the latter for withdrawing liquid therefrom; a valve operable for controlling passage of liquid through said pipe; means responsive to the presence of gasoline in said tank for opening said valve to permit the withdrawal of gasoline when the level thereof is above said inlet; means responsive to the presence of water in said tank operating 20 to close said valve when water accumulating in said tank rises to a determined level; and means controlled by said last mentioned means for rendering said first mentioned means ineffective to open said valve although the gasoline 25 level be above said inlet.

30 3. In a liquid-dispensing system including a gasoline storage tank, a suction pump, and a pipe connected to said pump and extending into said tank with its inlet above the bottom of the latter for withdrawing liquid therefrom; a valve for controlling passage of liquid through said pipe; a lever for operating said valve; a float carried by said lever and responsive to the presence of gasoline in said tank at a level above said inlet for operating said lever to open said valve; a second lever for operating said valve; and a float 35 carried by said second lever and responsive to accumulation of water at the bottom of said tank at a determined level for actuating said second lever to close said valve.

40 4. In a liquid-dispensing system including a gasoline storage tank, a suction pump, and a pipe connected to said pump and extending into said tank with its inlet above the bottom of the latter for withdrawing liquid therefrom; a valve for controlling passage of liquid through said pipe; a lever for operating said valve; a float carried by said lever and responsive to the presence of gasoline in said tank at a level above said inlet for operating said lever to open said valve; a second lever normally disconnected from said 45 valve; means for operatively connecting said second lever to said valve; and a float carried by said second lever and responsive to water accumulating at a determined level at the bottom of said tank for operating said second lever to close said valve.

45 5. In a liquid-dispensing system including a gasoline storage tank, a suction pump, and a pipe connected to said pump and extending into said tank with its inlet above the bottom of the latter for withdrawing liquid therefrom; a valve for controlling passage of liquid through said pipe; a lever for operating said valve; a float carried by said lever and responsive to the presence of gasoline in said tank at a level above said inlet for operating said lever to open said valve; a second lever for operating said valve; a float carried by said second lever and responsive to accumulation of water at the bottom of said tank 50 at a determined level for actuating said second

lever to close said valve; and means associated with said second lever and operative on actuation thereof to operate said first lever to overcome the buoyancy of its float to enable closing of said valve despite the presence of gasoline at a level 5 above said inlet.

55 6. In a liquid-dispensing system including a tank containing non-miscible liquids of differing specific gravities, a pipe for withdrawing liquid from said tank with its inlet above the bottom of the latter, and a valve for controlling passage of liquid through said pipe; means responsive to the presence of a liquid of determined specific gravity for opening said valve when said liquid is present in said tank at a level above the inlet to said pipe; and means responsive to the presence of a liquid of higher specific gravity for closing said valve when the latter liquid accumulates at the bottom of said tank at a determined level.

60 7. In a liquid-dispensing system including a tank for storing liquids, a pump for dispensing a liquid therefrom, a pipe connected to said pump and extending into said tank with its inlet above the bottom of said tank for withdrawing fluid therefrom, and a valve for controlling passage of liquid through said pipe; means responsive to the presence of a liquid of determined specific gravity for opening said valve when said liquid is present in said tank at a level above the inlet to said pipe; means responsive to the presence of a liquid of higher specific gravity in said tank for closing said valve when said later liquid accumulates at the bottom of said tank at a determined level; and means controlled by said last-mentioned means for rendering said first-mentioned means ineffective to open said valve despite the presence of said first-mentioned liquid at a level above said inlet.

65 8. In a liquid-dispensing system including a tank containing non-miscible liquids of differing specific gravities, a suction pump, and a pipe connected to said pump and extending into said tank with its inlet above the bottom of the latter for withdrawing liquid therefrom; a valve for controlling passage of liquid through said pipe, a lever for operating said valve; a float carried by said lever and responsive to the presence of a liquid of determined specific gravity in said tank at a level above said inlet for operating said lever to open said valve; a second lever; a float carried by said second lever and responsive to the presence of a liquid of higher specific gravity in said tank for actuating said second lever when said last mentioned liquid accumulates at a determined level at the bottom of said tank; and means associated with said second lever and adapted on actuation thereof to operate said first-mentioned lever to overcome the buoyancy of its float and close said valve for preventing discharge of said last-mentioned liquid by said pump.

70 9. In a liquid-dispensing system including a conduit connected to a liquid storage tank, a valve controlling the passage of liquid through said conduit, a lever connected to said valve for operating the latter and a liquid responsive float for actuating said lever; a second lever operatively connected to said valve; and a float carried by said second lever for actuating the latter to close said valve in response to the presence at a determined level in said tank of a liquid of higher specific gravity than that intended to be stored therein.

75 10. In combination with a valve controlling the outlet of a tank containing non-miscible liquids of different specific gravities, a lever operatively

- connected to said valve, a pivot for said lever, and
a float carried by said lever and responsive to
the presence in said tank at a level above said
outlet of a liquid of determined specific gravity
5 for operating said lever to open said valve; a
second lever mounted on said pivot; a float car-
ried by said second lever and responsive to the
presence at a determined level in said tank of
liquid of higher specific gravity for actuating said
10 second lever; and means operatively connecting
said second lever to said first lever for simultane-
ously actuating the latter to close said valve re-
gardless of the level in said tank of liquid of said
determined specific gravity.
- 15 11. In combination with a valve controlling the
outlet of a tank containing non-miscible liquids
of different specific gravities, a lever operatively

connected to said valve, a pivot for said lever, and
a float carried by said lever and responsive to the
presence in said tank at a level above said outlet
of a liquid of determined specific gravity for op-
erating said lever to open said valve; a second 5
lever mounted on said pivot; a float carried by
said second lever and responsive to the presence
at a determined level in said tank of liquid of
higher specific gravity for actuating said second lever;
and means carried by said second lever adapted 10
on actuation thereof to engage said first lever
and actuate the latter for closing said valve
despite the presence in said tank at a level above
said outlet of liquid of said determined specific 15
gravity.
